CLAIM

The ornamental design for a floating support structure, as shown and described.

DESCRIPTION

FIG. 1 is a top perspective view of a floating support structure showing my new design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a perspective view thereof, wherein the floating support structure has been fitted with an intake pump and filter apparatus; and,

FIG. 10 is an alternate perspective view thereof, wherein the floating support structure has been fitted with an intake pump and filter apparatus.

The Broken Lines in the drawings show portions of the floating support structure that form no part of the claimed design.

The broken lines in FIGS. 9 and 10 depicting an intake pump and filtration apparatus illustrate environmental structure that forms no part of the claimed design.

1 Claim, 10 Drawing Sheets
